CHRISTMAS TREE LAMP

Mario C. Pacini, 3000 Clay St., Newport Beach, Calif.

Filed June 1, 1964, Ser. No. 80,235

Term of patent 14 years

(Cl. D26—8)

FIG. 1

FIG. 2

FIG. 3

FIG. 4

FIGURE 1 is a perspective view of a Christmas tree lamp, showing my new design;

FIGURE 2 is a side elevational view, to a reduced scale, the opposite side being substantially a mirror image thereof;

FIGURE 3 is a top plan view, to a reduced scale; and

FIGURE 4 is an end elevational view, to a reduced scale, the opposite end being substantially a mirror image thereof.

I claim:

The ornamental design for a Christmas tree lamp, substantially as shown and described.
